UNITED STATES PATENT OFFICE.

DAVID DORN, OF ST. CLOUD, MINNESOTA.

GRAIN-SHOCKER.

1,135,366.

Specification of Letters Patent. Patented Apr. 13, 1915.

Application filed October 2, 1913. Serial No. 793,042.

To all whom it may concern:

Be it known that I, DAVID DORN, a citizen of the United States, residing at St. Cloud, in the county of Stearns and State of Minnesota, have invented a new and useful Grain-Shocker, of which the following is a specification.

This invention relates to machines for forming shocks from bundles of grain, one of the objects of the invention being to provide a machine of this character which can move forwardly in any desired manner and on which the bundles, when placed by any suitable means, will be arranged in parallel rows leaning toward each other, there being means for depositing the bundles, while in this position, upon the ground where they will remain standing in the form of a shock, the machine being so constructed as to automatically cease operating during the discharge of the shock onto the ground and to automatically reset so as to continue to operate as before, after the shock has been deposited on the ground.

Another object is to provide improved means for placing the bundles on end in position to be engaged by conveying means adapted to carry the bundles into the shock former.

A further object is to provide a shock former including parallel compartments, the walls of which converge upwardly, there being a switch of novel form for directing the bundles into the two compartments successively.

Another object is to provide improved means for automatically stopping the feeding of bundles into the shock former while a shock is being discharged from the former.

A further object is to provide means for rendering the bundle feeding means of the shock former inactive during the discharge of the shocks.

A further object is to provide means operated by one of the bundles of the shock for automatically tripping the shock former so as to discharge the shock upon the ground.

With the foregoing and other objects in view which will appear as the description proceeds, the invention resides in the combination and arrangement of parts and in the details of construction hereinafter described and claimed, it being understood that

changes in the precise embodiment of the invention herein disclosed, can be made within the scope of what is claimed, without departing from the spirit of the invention. 55

In the accompanying drawings the preferred form of the invention has been shown.

In said drawings:—Figure 1 is a plan view of the machine, a portion of the housing being broken away. Fig. 2 is a side elevation. Fig. 3 is a side elevation of a portion of the machine showing the mechanism employed for tripping and resetting the shock former. Fig. 4 is a plan view of the mechanism employed for tripping and resetting the shock former. Fig. 5 is an enlarged side elevation of a portion of the resetting mechanism of the shock former. Fig. 6 is a rear elevation of a portion of the mechanism used in manipulating the rack bar of the mechanism shown in Fig. 5. Fig. 7 is a detail view of the lifting cam used in connection with the structure shown in Fig. 6. Fig. 8 is an enlarged plan view of the tripping mechanism engaged and actuated by a bundle of the formed shock. Fig. 9 is an elevation of the front end portion of the machine. Fig. 10 is an elevation of the rear end portion of the machine. Fig. 11 is an end view of the bundle setting device and the means for actuating the same. Fig. 12 is a view similar to Fig. 11 and showing the setting device in its elevated position. Fig. 13 is a perspective view of a portion of the lower end of the bundle setting device. Fig. 14 is a rear elevation of the bundle setting device and of its actuating arm. Fig. 15 is a detail view of the cut-off gate, tooth guiding plate, and adjacent actuating means. Fig. 16 is an enlarged section through the conveyer actuating sprocket and its controlling clutch. Fig. 17 is an end view of the clutch. Fig. 18 is a plan view of the clutch actuating finger. Fig. 19 is an end view of the hub of the sprocket shown in Fig. 16. Fig. 20 is a perspective view of the clutch and adjacent parts. Fig. 21 is a perspective view of the stop gate and adjacent parts. 100 90 85 80 75 70 65 60 55

Referring to the figures by characters of references 1 designate a frame adapted to be connected to one side of a binder so as to move therewith, this frame being provided, at its front end, with a platform 2 and, at 105 one side of the front portion thereof, with

a deck 3 on which the bundles from the binder are adapted to be placed. Platform 2 has upstanding side walls 4 converging forwardly, one of these side walls 4 being curved at its front end so as to extend around the front end of the other side wall 4, as shown at 5, thus to form a curved passage 6 leading from the front end of the deck 3 around to the front portion of the platform 2. As shown in the drawings the upper ends of the walls of the platform can be connected by a top 7 and the deck 3 can also be provided with a housing 8. As shown particularly in Fig. 9, the bottom of 10 the deck is inclined downwardly toward the near wall 4 of the platform 2. Frame 1 is provided with parallel rearwardly extending side strips 9 the inner faces of which constitute backings for chains hereinafter referred to, these strips being rigidly mounted in any suitable manner as by means of arches 10.

Hingedly connected to the rear end of platform 2 is the bottom 11 of the shock former, this bottom being formed with a central upstanding core 12 the sides of which converge upwardly as shown at 13 and in planes parallel with the inner faces of the walls 9 a lip 11' is extended upwardly along each side edge of the bottom. The rear end portion of the core 12 is carried by a toothed wheel 14 designed to rotate on the ground and which is secured to a shaft 14', journaled in the core 12 and provided with a sprocket 15 for the purpose hereinafter set forth. The core 12 is hollow and the frame 1 has an extension 16 extending rearwardly therefrom and under the hollow core, there being a yoke 17 mounted for rotation upon the rear end portion of this frame extension and normally extending upwardly and forwardly, the upper end of the yoke being pivotally connected to the intermediate portion of a crank-shaped hanger 18, the ends of which are journaled within the sides of the core 12. A rack bar 19 is pivotally connected to the intermediate portion of the hanger 18 and extends forwardly within the core and above a gear 20 which is keyed or otherwise secured to a transverse shaft 21 extending under the frame 1 and supporting the same, this shaft being also connected to a supporting wheel 22 located under the center of the rear end portion of platform 2, as will be apparent by referring to Figs. 2 and 9. Hangers 23 extend from the arches 10 down through the open top of core 12 to frame 1.

It has been found that the bottom 11 of 60 the shock former can be hingedly connected to the front portion of the machine in a simple manner by utilizing the transverse shaft 21 as an axis about which said bottom can swing, as shown in Fig. 4.

Fixedly secured to the frame 1 back of gear 20 is a longitudinally slotted guide block 24 to one side of which is pivotally connected a shifting cam 25 having an arcuate slot 26, this cam being pivotally connected, as at 27, to one side of block 24 while a connecting rod 28 is pivotally connected to an arm 29 extending from the casting, the point of connection being indicated at 30. Actuating rod 28 extends rearwardly from the casting and within the hollow core 12, its rear end being pivotally connected to a lever 31 mounted to work in a substantially horizontal plane and pivotally mounted, as at 32 close to the center of the core 12. The outer end portion of this lever 31 projects through a slot 33 in the core and has an arm 34 extending rearwardly at an acute angle from the lever 31. A spring 35 is connected to lever 31 and to one wall of the core and serves to hold the lever normally pressed against the front end of slot 33 and the arm 34 normally extended obliquely across one of the compartments 36 formed at the sides of the core 12. Pivotally connected to the outer end portion of lever 31 and close to the core 12 is a trip 37 having a foot 38 adapted to bear against a backing block 39 which is located in the core and above the path of movement of lever 31. The trip 37 normally extends almost entirely across the compartment 36. It will be understood that when the trip 37 is pushed rearwardly by a bundle, the block 39 will prevent it from swinging inwardly toward the core 12 until after the foot 38 has passed the block 39 whereupon said foot will swing laterally in the slot 33 and trip 37 will swing against the side of core 12, as indicated by dotted lines in Fig. 8. The arm 34 will, during this movement, swing 105 inwardly against the wall of core 12 as shown in Fig. 8.

The arcuate slot 26 in the casting 25 receives a pin 40 which extends laterally from a slide 41, this slide being held to the guide block 24 by guide bolts 42 or the like extending through a slot 43 in slide 41. Slide 41 is also provided with a larger slot 44. The rack bar 19 bears downwardly on slide 41 and extending loosely through the slot 44 110 and bearing upon the bottom portion of slide 41 is a push bar 45, the upper end of which is loosely mounted on the rack bar 19 and is adapted to press against a pin 46 extending laterally from the rack bar 19. The lower end of the push bar extends through the guide block 24 and has a tooth or projection 47 which is normally spaced from gear 20 and is adapted to be brought into engagement with the gear when slide 41 is 120 raised by the casting 25.

It will be understood from the foregoing that when the trip 37 is pushed rearwardly,

lever 31 is actuated so as to pull on rod 28 and this, in turn, will pull on arm 29 and cause the slotted portion 26 of casting 25 to move upwardly, thus elevating slide 41. 5 This slide will promptly lift the rack bar 19 out of mesh with gear 20 and will throw the projection 47 into engagement with gear 20 so that the gear, while rotating, will push against bar 45 and cause this bar to push the 10 pin 46 and the elevated rack bar 19 rearwardly, thus throwing the upper end of the crank hanger 18 past its dead center, thereby causing the bottom of the shock former to swing downwardly, as indicated by dotted 15 lines in Fig. 3. After the rack bar 19 has been pushed back its greatest distance by the bar 45, the teeth of gear 20 will slip past the projection 47 as will be seen by referring to the dotted position of the parts in 20 Fig. 5, the parts being held in this position as long as there are any bundles pressing against the rearwardly extending arm 34 as will be hereinafter more fully described. Spring 35 serves to return the trip 37 and 25 slide 41 until rack bar 19 is in mesh with gear 20 and the toe 47 is disengaged from gear 20 whereupon the rotation of gear 20 returns bar 19 and bar 45 to their initial positions. 30 Arranged upon each of the upstanding side walls 4 of the platform 2 close to the rear ends of the walls are vertical shafts 48, each of which is provided near its lower end with a gear 49 constantly meshing with a 35 gear 50 secured to the transverse shaft 21. Each of these shafts has a sprocket 51 secured thereto and adapted to rotate therewith, this sprocket engaging and actuating a carrier chain 52. The carrier chains engage 40 sprockets 53 and 53' respectively. These sprockets are mounted in the front end portions of the walls 4, sprocket 53' being loosely mounted while sprocket 53 constitutes a driving element as will be herein- 45 after described. The inner flight of each chain 52 works along the inner surface of the adjacent wall 4. Each carrier chain has teeth 54 extending therefrom at regular intervals, each tooth being pivotally connected 50 to the chain and provided with a foot 55 ex- tending in a direction opposite to that in which the tooth is moving and adapted to slide along the adjacent wall 4 while in active position. This wall has a longitudi- 55 nal slot 56 therein beginning opposite the extension on a switch hereinafter men- tioned and normally mounted in this slot is a hinge leaf 57 hingedly connected to one end of a backing plate 58. The other end 60 of the backing plate is likewise connected to two links 59, the plate 58 being preferably formed with recesses 60 in which the links 59 are normally seated, the connections be- 65 tween links 59 and the wall 4 being indi-

cated at 61 in Fig. 15. The plate 58 is connected to the angle portion 63 of an L-shaped gate 64, this gate being pivotally connected as at 65 to a bracket or other structure extending from the wall 4. Obviously by pulling outwardly and forwardly upon 70 the hinge leaf 57, said leaf will be caused to swing laterally away from the wall 4 and plate 58 will also be moved laterally out of the slot 56, this plate pulling on the links 59 and causing them to swing laterally and 75 to pull upon the angle portion of gate 64. Said gate will thus swing laterally about its pivot 65 so that the active portion of the gate will be brought into position within slot 56 and at right angles to the wall 4 so 80 as to prevent the movement of bundles along the wall and past the gate, as shown by dotted lines in Fig. 15.

A rod 66 connects the hinge leaf 57 to one arm of a bell crank lever 67, the other arm 85 of this bell crank lever being connected by a rod 68 to a crank arm 69 extending from one end of a transverse shaft 70 journaled on the frame 1. This shaft 70 has an arm 71 between the ends thereof and which is connected, by a rod 72, to one side of the crank hanger 18. Thus it will be seen that when the bottom of the shock former is dropped for the purpose of discharging a shock, the 90 crank hanger 18 while moving rearwardly and downwardly will pull through rod 72 upon arm 71 and cause the crank arm 69 to pull, through the rods 68, upon the bell crank levers 67, thus pulling through rods 66 upon the hinge leaves 57 and causing plates 100 58 to move laterally out of slots 56 and the gates 64 to move to active positions across the passages at the inlet ends of the compartments in the shock former. Obviously, therefore, should the chains 52 be operating 105 while the plates 58 are out of position within the slots 56, the feet 55 will swing through the slots and the teeth 54 will thus become inactive and will not pull the engaged bundles toward the closed gates 64 but will 110 slip past the bundles thus leaving the same in position close to the gates but without moving into the shock former.

Each shaft 48 has a sprocket 73 loosely mounted thereon and provided with a hub 74 115 in the periphery of which are formed notches 75, such as shown in Fig. 19. A collar 76 rotates with each shaft 48 and has dogs 77 pivotally connected thereto at diametrically opposed points, these dogs being normally 120 inclined upwardly and outwardly so as not to engage the hub 74. A rod 78 is slidably mounted upon the outer side of each wall 4 and is provided, at its rear end, with an arcuate laterally extending finger 79 which is 125 normally removed from the path of the rotating dogs 77. This rod has a laterally extending pin 80 in the path of the lower arm

of the adjacent bell crank lever 67 so that, when said bell crank lever is shifted for the purpose of moving plate 58 out of slot 56 and shifting gate 64 to active position, the 5 bell crank lever will move against pin 80 and thus shift rod 78 longitudinally, thereby bringing finger 79 into the path of the dogs 77 so that, as these dogs rotate they will be brought against the finger and be shifted 10 inwardly thereby so as to engage the notches 75, thus coupling hub 74 and sprocket 73 to the rotating shaft 48. As soon as bell crank lever 67 moves back to its normal position, finger 79 moves away from the dogs 77 and 15 they are promptly moved back out of the notches 75 by a fixed cam 81 so that sprocket 73 will cease to rotate with shaft 48 after making one revolution.

A tripping arm 82 is pivoted in a slot 83' 20 in each wall 4 and has means for pushing against rod 78 as each bundle is discharged onto the platform 2 and directed toward one of the compartments of the shock former.

25 Each of the sprockets 73 which is normally loose on shaft 48, is engaged by a conveyer chain 83 extending rearwardly from the sprocket and engaging an idler sprocket 84 mounted upon the rear end portion 30 of the adjacent rearwardly extending strip 9. The inner flights of the chains 83 are arranged along the inner surface of the strips 9 and each chain has teeth 85 provided with feet 86 adapted to slide along 35 the strip 9 so as to hold the teeth 85 extended transversely of the adjacent compartment in the shock former during the rearward movement of the teeth while pressing a bundle longitudinally within the shock former.

40 While the teeth 54 carried by the outer flight of the chain 52 remote from the deck 3 are inactive, the corresponding teeth of the other chain 52 are active. In other 45 words, all of the teeth on the chain 52 nearest deck 3 are constantly active except while passing over slot 56 from which plate 58 has been withdrawn. The teeth on this chain 52 travel close to the path of a bundle 50 setting or placing device which, as shown particularly in Figs. 11 to 14 inclusive, is made up of a plate 87 hingedly connected to the deck 3 along a line parallel with the path of movement of the outer flight of the 55 chain 52, this plate 87 being provided, along its lower or hinged end, with an outstanding ledge 88 mounted to swing independently of plate 87 and held normally at right angles to said plate 87 by a spring 89. Ledge 88 60 has a latch 90 fixedly connected thereto and extending laterally therefrom beyond the hinge 91, this latch being provided with a beveled head 92 normally projecting through a slot 93 formed in an actuating

65 arm 94. This actuating arm is preferably forked as shown in Fig. 14 and is pivotally connected, at its upper end, to the upper portion of the back of plate 87. The lower end of arm 94 has an opening 95 through which extends a rod 96, this rod having a 70 pin 97 at its free end for preventing withdrawal of the rod from the opening 95. A spring 98 is mounted on the rod and bears at one end against the pin 99 on said rod and at its other end against the apertured 75 portion of arm 94. Rod 96 is pivotally connected by a pitman 101 to a crank arm 102 extending from the lower end of a vertical shaft 103. This shaft is actuated by the adjacent chain 52 which serves to rotate 80 sprocket 53 keyed on shaft 103. It is to be understood that any other suitable means may be utilized for transmitting motion from shaft 103 to the bundle placer so that said placer will be elevated whenever a 85 bundle is arranged thereon.

The rear portion of platform 2 has a partition 104 extending longitudinally of the center thereof and up to the front end of the core 12. This partition serves to divide 90 the back of the space between the walls 4 into two throats 105 and 106 respectively, the throat 105 discharging into the chamber 36 in the shock former while the throat 106 discharges into the chamber 107 of the shock 95 former and which is similar to the chamber 36. A V-shaped switch 108 extends from the front end of partition 104, its point being adapted to travel in an arc from the front end of one wall 4 to the front end of the 100 other wall 4. Arcuate wings 109 extend from the rear portion of the switch 108 and beyond opposite sides of the front end portion of partition 104, these wings being so proportioned and shaped that, when the point 105 of the switch 108 is bearing against one wall 4, one of the wings 109 is extending across the inlet end of the opposed throat 105 or 106.

110 The operation of the machine is as follows:—During the forward movement of the machine shaft 21 is rotated by wheel 22 and motion is transmitted therefrom through the gears 50 and 49 to the shafts 48 which, in turn, continually drive the chains 115 52 in the directions indicated by the arrows in Fig. 1. Let it be assumed that the switch 108 is in the position indicated by full lines in Fig. 1 and that the bottom of the shock former is held in raised position by the 120 crank hanger 18 being pulled forwardly past the dead center of the yoke 17, the forward movement of the rack bar 19 and the crank hanger 18 being limited by the crank coming against an arch or yoke 10 or in 125 any other preferred manner. A projection 45' limits the movement of bar 45. The dogs 77 are normally out of engagement

with the hubs 74 of sprockets 73 and, consequently, shafts 48 rotate ordinarily without transmitting motion to the chains 83. As the crank hanger 18 is extended in the 5 manner stated, the rod 72, shaft 70 and rod 68 together with the various parts connected thereto, hold the plates 58 in closed position within the slots 56. One of the chains 52 constantly rotates the shaft 103 and, consequently, the crank arm 102 will continuously 10 actuate the bell crank lever 100 so that the rod 96 will cause arm 94 to swing back and forth relative to the lowered placer plate 87, this being due to the fact that the latch 15 90 is out of engagement with arm 94 as long as ledge 88 is not weighted down. When, however, a bundle is placed on the inclined plate 87 the weight thereof will cause the ledge 88 to swing downwardly so as to move 20 the latch 90 upwardly at its free end. Thus, when the arm 94 is drawn against the plate 87 by the rod 96 during the actuation of crank arm 102, the head 92 of the latch will engage the slotted portion of arm 94 and 25 thus automatically lock the arm against movement relative to plate 87. Consequently during the continued rotation of the shaft 103 and the actuation of bell crank lever 100, the rod 96 will push, through spring 30 98, against the lower end of arm 94 and cause said arm as well as plate 87, to swing about hinge 91 as a pivot. Thus the bundle mounted on the placer plate 87 will be 35 swung upwardly against the near flight of chain 52 so that the teeth outstanding from said chain will engage the bundle and carry it into the passage 6, thence around through the passage against the switch 108 which will deflect the bundle into throat 105. In passing 40 through this throat the bundle will strike the trip or arm 82 so as to shift rod 78 longitudinally the finger 79 thus being brought into the path of the rotating dogs 77 and said dogs caused to couple sprocket 45 73 to shaft 48. Consequently chain 83 will be actuated until after the bundle has been placed on the shock former at which time the bundle will be brought into position to be engaged by one of the teeth 85. In passing 50 into throat 105, the bundle will engage the wing 109 thus shifting the switch to the position indicated by dotted lines in Fig. 1 whereupon the next time a bundle is directed through the passage 6 in the manner hereinbefore described, it will be deflected into 55 the throat 106. During this movement into the throat the bundle will strike the adjacent wing 109 and shift the switch 108 back to the position shown in full lines in Fig. 1 60 and the bundle will at the same time shift the adjacent trip or arm 82 so as to couple the other shaft 48 to the adjacent sprocket 73, thereby actuating the chain 83 for a short distance. This operation will con-

tinue until chamber 107 has been filled and, 65 as the last bundle of the shock is directed into the chamber 36, the first bundle will press against the trip 37 and cause it to swing rearwardly to the position indicated by dotted lines in Fig. 8, the arm 34 at the 70 same time being swung inwardly against the wall of the core 12. Rod 28 will thus pull upon the elevating cam or casting 25 so as to shift slide 41 and elevate the rack bar 19 and the bar 45. Projection 47 will be 75 brought into engagement with the rotating gear 20 and will be pushed upwardly and rearwardly thereby, thus causing the rack bar 19 to shift rearwardly and to throw the crank hanger 18 past its dead center, thereby 80 permitting the whole shock former to drop to the ground at its rear end. During this action the rod 72 pulls through arm 71 so as to rotate shaft 70 and cause the crank arm 69 to pull on the rod 68. Thus the bell 85 crank lever 67 will pull through rod 66 upon the hinge leaves 57, thereby causing the plates 58 to withdraw from slots 56 and causing the gates 64 to swing across the rear end of the throats 105 and 106. Consequently 90 should any bundles be directed into either throat during the forward movement of the machine, while the shock is being deposited on the ground, the teeth 54 will not operate to shift the bundles into the chambers 36 or 107 and furthermore the gates 64 will operate positively to prevent any bundle from falling into either of the chambers 36 or 107. When the shock former is lowered at its rear end in the manner described, the bell crank levers 67 strike the projections 80 so as to shift the rods 78 longitudinally and thus cause the dogs 77 to engage the hubs 74 of sprockets 73, one of 95 these dogs remaining constantly in active 100 position so that the sprockets 73 will thus be rotated continuously with the shafts 48 as long as the bell crank levers 67 press against the projections 80. Therefore the chains 83 will operate continuously to force the bundles 105 out of the chambers 36 and 107 during the forward movement of the machine, the bundles being left standing on end and the bundles leaving one of the chambers 36 being inclined upwardly toward and supported by the bundles leaving the other chamber 107. During this forward movement of the machine the bundles press the elongated arm 34 against the side of core 12 so that there is no danger of the lever 31 115 swinging back to its normal position under the action of spring 35. As soon as the last bundle has left the chamber 36, which will be simultaneously with the removal of the last bundle from chamber 107, arm 34 will 120 be released and, therefore, spring 35 will bring lever 31 back to its initial position and the trip 37 and arm 34 to their initial position 125.

tions. At the same time lever 31 will press against rod 28 and cause it to push back upon arm 29 whereby the lifting cam or casting 25 will swing downwardly and allow the slide 41 to move downwardly. Thus the bar 45 will swing downwardly away from gear 20 until the said bar rests upon the bottom portion of slide 41 and, at the same time, the rack bar 19 will drop onto gear 20. As the gear is rotating during the forward movement of the machine, it will draw the rack bar 19 longitudinally, this movement continuing until the last tooth of the rack bar has passed out of mesh with gear 20, at which time the crank hanger 18 passes its dead center, the weight of the bottom of the shock former causing the crank hanger to swing forwardly and downwardly until projection 45' comes against the lower end of the slide 41. During this movement the rod 72 rotates shaft 70 so as to cause the crank arms 69 to push through rods 68 against bell crank levers 67 so that the hinge leaves 57 and 59 and the plates 58 will be swung inwardly into the slots 56 and gates 64 will be swung out of active positions. Any bundles which may be standing in the throats 105 and 106 or within the passage 6 will thus be directed as before into the chambers of the shock former whereupon the operation hereinbefore described will be repeated. By providing the springs 98 upon the rods 96, the bundles can be held in up-standing positions while shaft 103 is making a one half revolution, thus enabling the tooth engaging the bundle to move it into the passage before the placer is forced back to its original position. In order to prevent bundles from falling under the placer while it is elevated, an arcuate shield 111 is extended downwardly from the outer or upper edge of the placer, as shown in Figs. 11 and 12.

It will be noted that each of the compartments in the shock former at the sides of the core 12 is overhung by an endless belt 112 extending longitudinally of the shock former, each belt being mounted on rolls 113 and 114, the rear rolls 114 being inclined downwardly and laterally so that the belt is given a twist. These rolls 113 and 114 can be mounted in any suitable manner and the sprocket 15 hereinbefore referred to is connected, by a chain 115, to a sprocket 116 secured to the shaft of the rolls 113. Thus it will be seen that when the toothed wheel 14 is dropped into contact with the ground during the release of the shock, said wheel will be rotated and motion will be transmitted therefrom through chain 115 to rolls 113 so that the belts 112 will be driven in the direction indicated by the arrow in Figs. 2 and 3, the lower flights of these belts engaging the tops of the bundles and

causing them to move rearwardly away 65 from the former while the core is being withdrawn from the shock. This discharging means thus operates to prevent the standing bundles from falling over during the withdrawal of the core. 70

It will be seen that when the machine is discharging a shock, the belt above the shock former will drop downwardly when the jointed supports are shifted as indicated by dotted lines in Fig. 3, thus causing the 75 belt to force the bundles into the stubble, making a substantial shock.

What is claimed is:—

1. The combination with a shock former having separate chambers, throats opening 80 into the respective chambers, and a bundle actuated switch for closing the inlet end of either throat, of endless conveyers for directing bundles against and past the switch and into the respective throats to shift the 85 switch, one of said conveyers constituting means for directing bundles to the switch, a shaft rotated by one of said conveyers, and means operated by said shaft for elevating a bundle against said bundle directing 90 means.

2. The combination with a shock former having separate chambers, a throat discharging into each chamber, and a bundle actuated switch for closing the inlet ends of 95 the chambers successively, of separate endless conveyers for directing bundles past the switch and into the respective throats, means for continuously actuating said conveyers during the forward movement of the shock former, a bundle placer mounted to 100 swing upwardly toward one of the conveyers to direct the bundles thereonto, and means operated by said conveyer for actuating the placer. 105

3. The combination with a shock former having separate chambers therein, throats opening into the respective chambers, a bundle actuated switch for successively closing the inlet ends of the throats, and a curved passage leading to the throats, of 110 separate endless conveyers for directing bundles past the switch and into the respective throats, one of said conveyers constituting means for carrying bundles along 115 the passage, means for continuously actuating the conveyers during the forward movement of the shock former, a movably mounted bundle placer mounted to swing upwardly toward the adjacent conveyer, 120 means operated by said conveyer for shifting the bundle placer to direct the bundle against the conveyer.

4. The combination with a shock former having separate chambers therein, throats opening into the respective chambers, a bundle actuated switch for successively closing the inlet ends of the throats, and a 125

curved passage leading to the throats, of 5
separate endless conveyers for directing
bundles past the switch and into the respec-
tive throats, one of said conveyers consti-
tuting means for carrying bundles along
the passage, means for continuously actuating
the conveyers during the forward
movement of the shock former, a movably
mounted bundle placer mounted to swing
10 upwardly toward the adjacent conveyer, ac-
tuating mechanism driven by said conveyer,
and means operated by the weight of a bun-
dle placed upon the placer for coupling said
actuating means to the placer to elevate
15 said bundle against the conveyer.

5. The combination with a shock former
and a conveyer for directing bundles there-
to, of a bundle placer mounted to swing
upwardly toward the conveyer, an actuating
20 element mounted to swing relative to and
connected to said placer, means operated by
the conveyer for shifting said actuating
means, and means operated by a bundle
when mounted on the placer for coupling
25 said placer to the actuating means to shift
the bundle against the conveyer.

6. The combination with a shock former
and a conveyer for directing bundles there-
to, of a bundle placer, an element connected
30 thereto and adapted to swing independently
thereof, means operated by the conveyer for
swinging said element during the actuation
of the conveyer, a yieldable bundle support-
ing device connected to the placer, and
35 means movable with said device to couple
the placer to the movable element when sub-
jected to the weight of a bundle, said coupled
placer constituting means for shifting
the bundle thereon into engagement with
40 the conveyer.

7. The combination with a shock former
and a conveyer for directing bundles there-
into, of a bundle placer mounted to swing
upwardly toward the conveyer, an element
45 connected to and adapted to swing inde-
pendently of the placer, means operated by
the conveyer for actuating said element, a
yieldably supported ledge connected to the
placer, a locking element carried thereby
50 and normally disengaged from said swing-
ing element, said locking device being shift-
able into engagement with the swinging ele-
ment when the ledge is subjected to the
weight of a bundle.

55. 8. The combination with a shock former
and a conveyer for directing bundles there-
into, of a bundle placer mounted to swing
upwardly toward the conveyer, an element
60 connected to and adapted to swing inde-
pendently of the placer, yielding means op-
erated by the conveyer for actuating said
element, a yieldably supported ledge con-
nected to the placer, a locking element car-
ried thereby and normally disengaged from

said swinging element, said locking device 65
being shiftable into engagement with the
swinging element when the ledge is subject-
ed to the weight of a bundle.

9. The combination with a shock former,
a throat opening thereinto, and a continu-
ously moving conveyer for directing bundles
into the throat, of a normally inactive con-
veyer extending longitudinally of the shock
former, means for actuating the continu-
ously moving conveyer, and means under 75
the control of a bundle entering the throat
for coupling the normally inactive conveyer
to the actuating means during a portion of
the movement of said bundle within the
throat. 80

10. The combination with a shock former,
a throat opening thereinto, and a continu-
ously moving conveyer for directing bundles
into the throat and shock former, of means
for continuously actuating said conveyer, a 85
normally inactive conveyer extending longi-
tudinally of the shock former, means oper-
ated by a bundle during a portion of its
movement within the throat for automatic-
ally coupling said normally inactive con- 90
veyer to the actuating means, and means for
uncoupling prior to the entrance of the
bundle into the shock former.

11. The combination with a shock former
having a bottom hingedly mounted at its 95
front end, a revoluble supporting wheel,
and a gear movable therewith, of a support-
ing yoke, a hanger pivotally connected
thereto and normally mounted off center for
supporting the hinged bottom in raised po-
sition, means for directing bundles into the
shock former, separate gear engaging de-
vices normally out of engagement with the
gear, means operated thereby when moved
in one direction for releasing and lowering 100
the bottom and, when moving in the oppo-
site direction to elevate the bottom to its
normal position, and bundle operated means
for shifting said device successively into
engagement with opposed portions respec- 110
tively of the gear.

12. The combination with a shock former
having a hinged bottom, means for direct-
ing bundles into the shock former, and co-
operating means for holding the bottom of 115
the shock former raised, of a supporting
wheel, a gear revoluble therewith, a tri-
pping element within the shock former and
adapted to be actuated by a bundle when
the former is filled, means shiftable by said
element into engagement with the gear for
actuating the bottom supporting means to
release said bottom, and means under the
control of the tripping element and co-
operating with the gear, to return the bot- 120
tom to its normal or raised position.

13. The combination with a shock former,
having a hinged bottom, means for direct-

- 3
- 5 ing bundles into the shock former, and co-operating means for holding the bottom of the shock former raised, of a supporting wheel, a gear revoluble therewith, a tripping element within the shock former and adapted to be actuated by a bundle when the former is filled, means shiftable by said element into engagement with the gear for actuating the bottom supporting means to
- 10 release said bottom, means movable with the tripping element and co-operating with the gear to return the bottom to its normal or raised position, and means operated by the bottom supporting means for stopping
- 15 the bundle directing means while the bottom is lowered.
14. The combination with a shock former having a hinged bottom, means for normally supporting the bottom in raised position, and a conveyer for directing bundles onto said bottom, of a supporting wheel, a gear revoluble therewith, a tripping element adapted to be actuated by a bundle in the shock former when said former is filled,
- 20 means operated by said tripping element when shifted by a bundle, for engaging the gear to actuate the supporting means and release the bottom during the forward movement of the shock former, means controlled
- 25 by the tripping device for engaging the gear to elevate the bottom and supporting means to their normal positions, and means movable with the tripping device for delaying the action of said bottom raising means until
- 30 35 after the shock former has been emptied.
15. The combination with a shock former having a hinged bottom, means for normally supporting the bottom in raised position, and a conveyer for directing bundles onto said bottom, of a supporting wheel, a gear revoluble therewith, a tripping element adapted to be actuated by a bundle in the shock former when said former is filled, means operated by said tripping element
- 40 45 when shifted by a bundle for engaging the gear to actuate the supporting means and release the bottom during the forward movement of the shock former, means controlled by the tripping device for engaging the gear
- 50 to elevate the bottom and supporting means to their normal positions, means movable with the tripping device for delaying the actuation of said bottom raising means until after the shock former has been emptied, a
- 55 conveyer for engaging the bundles in the shock former, an operating shaft, and means for automatically coupling said conveyer to the operating shaft while the bottom is in lowered position.
- 60 16. The combination with a shock former having a hinged bottom, a normally inactive conveyer extending longitudinally of the former, a drive shaft, and means for directing bundles into the shock former, of a revo-

luble supporting wheel, a gear movable 65 therewith, tripping means in the shock former for engagement by a bundle when the former is filled, means for normally holding the bottom raised, means operated by the tripping device for engaging the gear to 70 release the bottom from its elevated position, means operated by the bottom supporting means during the release of the bottom for coupling the conveyer to the drive shaft, means shiftable with the tripping element and adapted to be successively engaged by the bundles during their discharge from the former for holding the conveyer coupled to the drive shaft, means for automatically returning the tripping element to its 80 initial position when the shock former is emptied, and means for engaging the rotating gear during the return of the tripping device to its normal position for elevating the bottom of the former to its raised position.

17. The combination with a shock former having a hinged bottom, and a conveyer for directing bundles onto said bottom, said conveyer including an endless chain and 90 teeth pivotally connected to the chain and having feet extending therefrom, of a backing plate for engagement by the teeth to hold the teeth in active position for engaging and propelling bundles toward the 95 former, a gate connected to the plate, a tripping element within the former adapted to be actuated by a bundle when the former is filled, means for supporting the bottom of the former in raised position, means operated by the tripping element for automatically releasing the bottom during the forward movement of the former, means operated by the bottom during its downward movement for shifting the backing plate 105 away from the teeth to render the teeth inactive and to shift the gate across the path of the bundles being supplied to the former.

18. The combination with a shock former having a hinged bottom, and a conveyer for directing bundles onto said bottom, said conveyer including an endless chain and teeth pivotally connected to the chain and having feet extending therefrom, of a backing plate for engagement by the teeth to hold the teeth in active position for engaging and propelling bundles toward the former, a gate connected to the plate, a tripping element within the former adapted to be actuated by a bundle when the former is 110 filled, means for supporting the bottom of the former in raised position, means operated by the tripping element for automatically releasing the bottom during the forward movement of the former, means operated by the bottom during its downward movement for shifting the backing plate 115 away from the teeth to render the teeth inactive and to shift the gate across the path of the bundles being supplied to the former.

19. The combination with a shock former having a hinged bottom, a normally inactive conveyer extending longitudinally of the former, a drive shaft, and means for directing bundles into the shock former, of a revo-

active and to shift the gate across the path of the bundles being supplied to the former, and means operated by the tripping element for automatically elevating the bottom 5 to its raised position and returning the backing plate to its active position, and the gate to its inactive position.

In testimony that I claim the foregoing as my own, I have hereto affixed my signature in the presence of two witnesses.

DAVID DORN.
